M. G. WINTERS.
RAILROAD TIE.
APPLICATION FILED APR. 26, 1917.

Patented May 7, 1918.

1,265,572.

UNITED STATES PATENT OFFICE.

MARSHALL GUY WINTERS, OF EVERETT, PENNSYLVANIA.

RAILROAD-TIE.

Specification of Letters Patent.

Patented May 7, 1918.

1,265,572.

Application filed April 26, 1917. Serial No. 164,684.

To all whom it may concern:

Be it known that I, MARSHALL GUY WINTERS, a citizen of the United States, residing at Everett, in the county of Bedford and State of Pennsylvania, have invented certain useful Improvements in Railroad-Ties, of which the following is a specification, reference being had therein to the accompanying drawings.

10 The present invention has reference generally to improvements in that class of inventions known as ties and fasteners and more particularly relates to improved railroad ties.

15 As the primary aim and object the present invention contemplates the provision of a novel tie embodying sections formed of reinforced concrete, improved metallic connecting means being anchored in the adjacent ends of the sections for spacing the sections and to afford resiliency to the tie as a whole when subjected to the strain caused by the rolling stock passing thereover.

20 It is an additional and equally important object to provide improved seats in the sections for receiving and supporting the rail sections.

25 Still further the invention includes the provision of coöperative means anchored in the sections and engageable with the upper surfaces thereof but separate therefrom for removably clamping the rails in position.

30 Among the other aims and objects of the present invention may be recited the provision of a device of the character mentioned 35 with a view to compactness, and in which the number of parts are few, the construction simple, the cost of production low and the efficiency high.

40 Other objects as well as the nature, characteristic features and scope of this invention will be more readily apparent from the following description taken in connection with the accompanying drawings and 45 pointed out in the claim, forming a part of this specification.

45 The preferred embodiment of the present invention is clearly illustrated in the accompanying drawings, in which:—

50 Figure 1 is a side elevation of the invention.

Fig. 2 is an enlarged longitudinal section,

Fig. 3 is a top plan of the invention, and

Fig. 4 is a perspective detail of the wedge 55 block.

Similar characters of reference are em-

ployed in all of the above described views, to indicate corresponding parts.

Referring now, more particularly, to the accompanying drawings I provide a tie embodying a plurality of spaced yet connected sections each section including a body 1 formed of concrete reinforced by metallic sheets 2 arranged longitudinally and horizontally thereof in spaced relation throughout the height. A metallic bar 3 having anchoring plates 4 formed on the respective ends and anchored in the adjacent ends of the sections when they are molded, serves as a means for yieldingly connecting the sections. Bolts 5 have anchoring heads 6 formed on the angularly bent ends so as to effectively maintain the bolts in a proper position in the body when they are being molded, the outer portions 6' of the bolts 75 being extended upwardly and projecting above the upper surfaces of the sections and arranged perpendicularly thereto. As is apparent upon reference to Fig. 2 pairs of these bolts are arranged in spaced relation 80 while the angularly bent ends extend in opposite directions, this arrangement being for a purpose to be described.

In order to provide the improved rail seats intimated above, I employ wood blocks 85 7 the side edges of which are beveled inwardly toward the lower edges as indicated by the numeral 8 so that the blocks may be snugly fitted in the transversely arranged recesses 9 having the inclined side walls 10 90 corresponding to the beveled edges 8 to permit of the upper surface of the blocks being arranged in alignment with the upper surface of each section. The blocks, of course, are provided adjacent one edge with spaced 95 bolt receiving openings 11 for accommodating one pair of bolts 5 and are provided on their opposite edge with spaced inwardly extending slots 12. Bolts 13 extend transversely through the blocks in spaced relation to each other and have their heads embedded in one of the free edges while nuts 14 are engaged on the threaded extremities and are embedded in recesses as indicated in Fig. 4. As is apparent this arrangement 105 serves to brace the blocks and reduce the possibility of splitting thereof when they are subjected to the severe strain caused by the rolling stock passing over the rails 15 positioned thereabove.

110 For the purpose of removably clamping the rails 15 in position above the blocks 1

have provided rail base engaging and clamping plates 16 the flanged ends 17 of which are arranged in the transverse grooves 18 in the sections 1 while the opposite ends extend inwardly and are inclined upwardly as at 19 to effectively engage the base flanges of the rail. These plates, of course, are also provided with bolt receiving openings 20 to permit of an effective engagement with the upwardly extended ends of the bolts 5. Lock washers 21 are arranged on the bolts above the plate 16 and engaged by nuts 22 and serve as a means for clamping the plates in the position illustrated.

In view of the foregoing description it is believed that the advantages of the invention will be readily apparent. However, it may be stated that the bolts 5 being anchored in the bodies serve to reinforce the bodies and to prevent longitudinal movement of the blocks in the recesses besides facilitating the clamping of the rails in position.

It will be understood that the foregoing description and accompanying drawings comprehend only the general and preferred embodiment of my invention and that various minor changes in detail of construction, proportion and arrangement of the parts may

be made within the scope of the appended claim and without sacrificing any of the advantages of my invention.

Having thus fully described my invention, what I claim as new and desire to secure by Letters-Patent is:

A railroad tie embodying a pair of spaced sections each of which includes a body formed of concrete, means for reinforcing the body, metallic means anchored in and connecting the sections when they are molded for imparting a resiliency to the tie as a whole, the upper surface of each of the sections being provided with a transverse groove having inclined side walls, blocks formed of wood having their outer edges beveled to abut the inclined walls of the recesses when the blocks are situated therein, bolts extending transversely through the blocks for bracing the blocks and other bolts anchored in the bodies of the sections and engaging the blocks for preventing longitudinal movement of the blocks and adapted to be engaged by rail clamping means.

In testimony whereof I affix my signature.

MARSHALL GUY WINTERS.
